UNITED STATES PATENT OFFICE.

CLARENCE W. COLEMAN, OF WESTFIELD, NEW JERSEY, ASSIGNOR TO THE HALL SIGNAL COMPANY, A CORPORATION OF MAINE.

SWITCH INSTRUMENT.

1,010,864.

Specification of Letters Patent.

Patented Dec. 5, 1911.

Application filed October 9, 1909. Serial No. 521,927.

To all whom it may concern:

Be it known that I, CLARENCE W. COLEMAN, a citizen of the United States, residing at Westfield, in the county of Union and State of New Jersey, have invented certain new and useful Improvements in Switch Instruments, of which the following is a specification, reference being had therein to the accompanying drawings; forming part 10 thereof.

My invention relates generally to devices for controlling the circuits of signals or other railway traffic controlling apparatus, and more particularly to devices wherein 15 such control is effected by the movement of a railway switch.

In block signaling systems for controlling railway traffic, in order to automatically apprise a train entering a block of the condition 20 of the switches in the block, it is essential that the opening of a switch should affect the signals at the entrance of the block. As a further element of safety or convenience, local signals may also indicate the 25 condition of the switches. This control of signals entails the automatic control of a number of electric circuits, each independently of the others and in a manner required by each individual circuit. More- 30 over, railway switches are of various kinds and are variously combined with signals and signal circuits, so that a large variety of conditions of circuit control are met with in the many uses of a switch instrument.

It is an object of my invention to provide a device for thus automatically controlling a plurality of circuits by the movement of a switch, which may be adjusted to variously control the circuits as may be de- 40 sired, so as to provide a switch instrument of universal application, and which will open the back contacts and close the front contacts by a forced movement, and will be extremely simple and easy to arrange, ad- 45 just and maintain.

Another object of my invention is to so tightly incase the contact make-and-break devices as to reduce to a minimum injury from moisture and deleterious gases, while 50 at the same time permitting a free entrance of the conducting wires to the casing.

Another object is to provide novel means for positively adjusting each contact controlling member independently about its 55 support and for clamping it thereto.

Other objects and advantages of my invention will appear from the following description.

I shall now describe my invention with reference to the accompanying drawings 60 and shall thereafter point out my invention in claims.

Figure 1 is a plan view of my switch instrument with the cover broken away. Fig. 2 is a sectional elevation on the line 2—2 of 65 Fig. 1. Fig. 3 is an enlarged detail of the segment shaft. Fig. 4 is an enlarged detail, partly in section, of a contact-controlling segment. Fig. 5 is a diagram showing my instrument connected to a railway switch. 70

In the specific embodiment of my invention illustrated in the drawings, I show four sets of contacts and their respective controlling devices, though this number may be modified as desired. The parts are inclosed 75 in a casing 11, having two compartments, one of which contains the working parts and moving contacts, and the other the binding posts and provisions for getting the wires to them. A cover 12 for the casing 11 is hinged at the 80 back as shown and closes both compartments, but it is made with a groove for receiving a rubber gasket 13 so as to tightly seal the inner compartment containing the working parts and thus prevent the parts 85 from being harmed by moisture, dust, insects or injurious gases. For each set of contacts there are three binding posts, 14, 15 and 16, and the electrical connections are carried through the stationary or immovable 90 wall 17 between the two compartments by means of these binding posts, which pass through insulated bushings 18 and blocks 19, which hermetically seal the openings in the wall 17. Thus all the electrical contacts 95 and their binding posts are congregated, greatly facilitating the attaching of the conducting wires. An operating rock-shaft 20 enters the inner compartment and is journaled in the walls with finished bearings 100 having a close working fit, thus leaving the compartment exceedingly tight. No wires have to be carried to the inner compartment, and therefore it may be tightly closed and the wires may yet freely enter and leave the 105 outer compartment without affecting the tightness of the inner compartment.

Each of the four sets of contacts shown in the drawings consists of a spring contact member or lever 21, having a plurality of 110

leaves of different length and attached at the bottom to the lower binding post 16 by a bracket 22, and at its upper end provided with two contact fingers, one adapted to engage with a front stop 24 on a small bracket attached to the upper binding post 14, and the other to engage a back stop 23, on a large bracket attached to the middle binding post 15. In the construction shown in 5 the drawings, the back stop 23 is normally closed and the front stop 24 open; in other words, the lower binding post is normally in electrical connection with the middle binding post, and not in such connection 10 with the upper binding post.

To actuate the spring contact member 21 and break the contact with the back stop 23 and make the contact with the front stop 24, I employ contact-controlling segments 30 15 mounted on the shaft 20, one for each set of contacts, and adapted in their rotation to engage a roller 31 journaled in lugs 32 on the spring contact member 21, and to press the spring contact over away from the back 20 stop 23 and against the front stop 24. By this operation, the back contact of each 25 spring is positively forced open and the front contact is positively forced closed and remains closed as long as the segment is on 30 the roller. When the segment rotates off the roller, the resiliency of the spring contact member 21 returns the contacts to their original position shown in the drawings, opening the contact at the front stop 24 35 and closing the contact at the back stop 23. The contact-controlling segments 30 have a roller tread 33 of suitable material on a block of insulating material 34 and fastened by screws or bolts 35 which pass through insulating bushings 36. Nuts 37 on the ends 40 of the screws rest in insulating washers 38, the spaces 39 about the nuts 37 being filled with sulfur or other suitable setting insulating material. To open or close contact at 45 as many points of the movement as there are segments, each one of the segments is independently adjustable on the shaft 20. To so adjust the segments on the shaft and at the same time to clamp them in position, I 50 employ an adjusting and clamping screw-threaded part or bolt 40. The arbor of the segment which fits over the shaft 20 is made in the form of a split clamp, and the adjusting and clamping bolt 40 passes through 55 a clearance hole and is free to turn therein. In the shaft 20 is a groove with worm teeth 41 cut in for each segment. To set a segment, it is slipped on the shaft to the groove and the adjusting and clamping bolt 40 is 60 turned until the head comes against the adjacent jaw of the segment arbor, and then two nuts are placed on the end of the bolt where it projects through the other jaw of the segment arbor and locked together close 65 to this jaw. The segment then may be ad-

justed by turning the bolt, so as to feed the segment about the shaft to the desired position, then the bolt may be held to prevent it from turning and the nut nearer the segment jaw screwed up so as to clamp the segment tightly on the shaft, and the outer or jam nut screwed up to perform its locking function. Thus a solid joint is formed, which makes it impossible for the segment to shift on the shaft, on account of the engagement of the teeth in the shaft with the screw threads, the locking of the bolt and the clamping of the segment arbor on the shaft.

To rotate the shaft 20 with the movement 80 of the switch, a crank 42 is rigidly secured to the end of the shaft 20, which projects from the casing, and a connecting rod 43 is attached, one end to the crank 42 by means of a jaw and pin, and the other end to the 85 switch point by the same means, passing underneath the rail, as shown in Fig. 5. The switch-operating rod 45 is shown. The other parts of the switch-operating means are not shown, since they are of well known 90 construction. When the switch is moved to open it, it rotates the shaft 20 a part of a revolution, and when it is closed, the shaft is thereby rotated back to its original position. A hood 44 attached to the side of the 95 casing by hooks 49 projecting from the hood and screws 50, passing through the hood and entering the casing near the base, extends over the trunking and protects the wires entering the switch instrument. At the opposite side of the casing a covering plate 48 covers an opening like that at which the hood is located and is similarly held in position by hooks 49 and screws 50, and may be interchanged with the hood so that the 100 hood may be attached to either side. Securing lugs 25, in which screw holes are provided, serve as legs for the casing, while a staple 26 and an eye-bolt 27 and hasp 28 hold the cover 12 closed. A lock nut 29 on 105 the eye-bolt locks the cover and the hasp 28 is hinged to the lock nut 29 and serves as a handle for the nut. A pad-lock may be used to prevent the hasp being taken off the staple without authority.

Through the rotation of the shaft 20 the contacts are opened and closed as above described. The normal position is shown in the drawings, with the switch closed to the main line. If the circuit to be controlled is 110 a shunt for a track circuit, for example, the wires are connected to the lower and upper binding posts, and on the first slight movement of the opening of the switch point the 115 spring is forced out and makes the front contact 24. If it be a line circuit to be controlled, it will in most cases be opened when the switch is opened and in that case the wires are connected to the lower and middle binding posts, and on the first slight 120 125 130

movement of the switch to open it, the back contact 23 is forced open. It may be necessary to open or close a circuit on the completion of the movement of the switch point, and in that case the segment is set in the position shown for the rear contact-controlling segment far enough away from the roller to just force the spring over against the front contact 24 at the very end of the movement of the switch, or the segment may be set on the roller so as to roll off at the end of the movement of the switch and allow the spring to close the back contact 23 by an adjustment which will be obvious, or the segments may be set to close or open the contacts during any part of the movement of the segments, as desired. In this way, any number of contacts may be controlled in any manner and at any point of time in the movement of the switch required by the needs of the signaling system.

It is obvious that various modifications may be made in the construction shown and above particularly described within the principle and scope of my invention.

I claim:

1. An electric switch instrument comprising a rock shaft, an electrical contact device, a contact-controlling member coöperative therewith and secured upon the rock shaft, and adjusting and clamping means coöperative with the shaft to positively angularly adjust the contact-controlling member about the shaft and to lock the member in adjusted position on the shaft.

2. An electric switch instrument comprising a rock shaft, a plurality of electrical contact devices; a plurality of contact-controlling members respectively coöperative therewith and each secured upon the rock shaft, and adjusting and clamping means for each contact-controlling member coöperative with the shaft to positively angularly adjust the contact-controlling member about the shaft and to lock the member in adjusted position on the shaft.

3. A railway switch instrument comprising a rock shaft, two electrical contacts, a contact lever coöperative with the two electrical contacts, a movable contact lever-controlling member carried by the rock shaft and coöperative with the contact lever, an open top casing comprising two compartments separated by a wall, the rock shaft, the contact-lever-controlling member, the electrical contacts and the contact lever being located in one of the compartments, the two electrical contacts and the contact lever being carried by the wall, with binding posts secured to and extending through the wall and adapted to have the conducting wires secured thereto in the other compartment; and a cover for the casing covering both compartments and combined therewith so that it may be opened for access to both

compartments and will form a tight enclosure of the compartment first mentioned.

4. An electric switch instrument comprising a rock shaft having longitudinally extending teeth thereon, a plurality of contact members, a contact controlling segment on the shaft for each contact member, each segment being independently angularly adjustable on the shaft, an adjusting and clamping screw for each segment the thread of which directly engages the teeth on the rock shaft to effect the adjustment of the segment, and clamping means combined with the screw to lock the segment on the shaft.

5. A railway switch instrument comprising a movable member, means for actuating the movable member, an electrical contact and a contact lever in control thereof, a contact-lever-operating member actuated by the movable member, an open top casing for the parts comprising two compartments separated by a partition wall; the movable member, the electrical contact, the contact lever and the contact-lever-operating member being located in one of the compartments and the movable member entering a wall of such compartment and the binding posts for the electrical contact and the contact lever being secured to and extending through the partition wall and adapted to have the conducting wires secured thereto in the other compartment; and a cover for the casing covering both compartments and combined therewith so that it may be opened for access to both compartments and will form a tight enclosure of the compartment first mentioned.

6. A railway switch instrument comprising a movable member, means for actuating the movable member, an electrical contact and a contact lever in control thereof, a contact-lever-operating member actuated by the movable member, an open top casing for the parts comprising two compartments separated by a partition wall; the movable member, the electrical contact, the contact lever and the contact-lever-operating member being located in one of the compartments and the movable member entering a wall of such compartment and the binding posts for the electrical contact and the contact lever being secured to and extending through the partition wall and adapted to have the conducting wires secured thereto in the other compartment; and a single cover for the casing covering both compartments and hinged at one end of the casing so that it may be opened for access to both compartments and combined with the casing so that it will form with one of the compartments a tight enclosure of the compartment first mentioned.

7. An electrical switch instrument comprising, a rock shaft, an electrical contact device, a contact-controlling member coöperative therewith and secured upon the rock

shaft, the contact-controlling member having a split clamp embracing the rock shaft, the rock shaft having worm teeth thereon, a threaded adjusting bolt passing loosely through the split clamp and engaging the teeth on the rock shaft, and means for clamping the bolt and the split clamp in adjusted position.

8. An electric switch instrument comprising, a rock shaft, an electrical contact device, a segment coöperative with the contact device, the segment having a split clamp

embracing the rock shaft, the rock shaft having worm teeth thereon, a threaded adjusting bolt passing loosely through the split clamp and engaging the teeth of the rock shaft, and means for clamping the bolt and the split clamp in adjusted position. 15

In testimony whereof I have affixed my signature in presence of two witnesses.

CLARENCE W. COLEMAN.
